UNITED STATES PATENT OFFICE

161,934

REMOTE CONTROL HOUSING FOR ANTENNA ROTATOR

Richard H. Jordan, Mansfield, Ohio, assignor to
The Alliance Manufacturing Company, a corporation of Ohio

Application November 19, 1948, Serial No. 149,726

Term of patent 14 years

(Cl. D26—14)

To all whom it may concern:

Be it known that I, Richard H. Jordan, a citizen of the United States, in the city of Mansfield, county of Richland, and State of Ohio, have invented a new, original, and ornamental Design for Remote Control Housing for Antenna Rotator, of which the following is a specification, reference being had to the accompanying drawings, forming a part hereof;

Figure 1 is a top plan view of a remote control housing showing my new design;

Figure 2 is a front elevational view thereof;

Figure 3 is a side elevational view looking at the right end thereof as viewed in Figure 2;

Figure 4 is a rear elevational view; and

Figure 5 is a perspective view as viewed from a point above and to the right of the front of the housing.

I claim:

The ornamental design for remote control housing for antenna rotator, substantially as shown.

RICHARD H. JORDAN.
